UNITED STATES PATENT OFFICE.

OSCAR LEONARD BAXTER, OF COLUMBUS, OHIO, ASSIGNOR TO SOLAR METAL PRODUCTS COMPANY, OF COLUMBUS, OHIO, A CORPORATION OF NEW YORK.

DOOR OR WINDOW CONSTRUCTION.

1,278,827.

Specification of Letters Patent. Patented Sept. 17, 1918.

Application filed June 29, 1917. Serial No. 177,639.

To all whom it may concern:

Be it known that I, OSCAR LEONARD BAXTER, a citizen of the United States, residing at Columbus, in the county of Franklin and State of Ohio, have invented certain new and useful Improvements in Door or Window Constructions, of which the following is a specification.

This invention relates to door or window construction and has for its main object the provision of a peculiarly formed structure carried by the outer edge of the trim, which serves as an abutment for the plaster and also serves as a gage by which the thickness of the plaster may be governed. The primary advantage of this structure results from the fact that the joining edge between the plastered wall and the door or window frame construction is completely hidden. Additionally, it is well known that where the plaster is run up flush to an exposed edge, this plaster frequently chips or cracks off, thus giving an unsightly appearance. This my invention overcomes because the abutment for the plaster is located beneath the trim body.

A further object of my invention resides in forming the jamb, trim and plaster gage and abutment from one piece which may be subsequently shaped and joined to form the desired type of door or window frame and which is then placed in position within the building and the wall built into the same. By this arrangement, the cost is very materially reduced.

The preferred embodiment of my invention is shown in the accompanying sheet of drawings, in which similar characters of reference designate corresponding parts, and 40 in which:

Figure 1 is a view showing my invention applied to a door frame, and,

Fig. 2 is an enlarged section taken on line 2—2 of Fig. 1, showing the frame itself 45 in solid outline and the building wall, plaster and anchors in dotted outline.

By referring to Fig. 2, it will be noted that the jamb portion 1 and the trim portions 2 are integrally formed. The desired 50 shape is given the trim and the combined framework is of a size slightly larger than the width of the building wall. The rear

portion 3 of the trim is also shaped to present a height somewhat to a higher level than the edge of the plaster 4 and this portion 55 is then provided with a downturned bend 5. The downturned bends 5 terminate in a substantially Z-shaped formation whose legs 6 and 7 project inwardly toward the door opening and whose intermediate portion 8 is 60 substantially parallel with the flange 5 and projects toward the building wall. The in-turned legs 7 are in substantially the same plane as the portion 2 of the trim, so that the building wall, which in this case is 65 shown as being formed of a plurality of blocks 9 may be easily fitted in position. Reference to the drawing will show that the in-turned legs 7 serve primarily to form a base against which the anchors 10 are secured, these anchors being shown in the form of wires having an over-turned head and embedded between the courses of the blocks 9. In this manner, the entire frame 70 is rigidly held in position. The intermediate portions 8 of the Z-shaped flange terminations serve as an abutment against which the plaster 4 rests, while the inwardly projecting legs 6 serve both as a gage to which the plasterer may work in determining the thickness of the plaster and also as covering the edge defining the boundary of the plaster. In other words, the corner formed by the plaster where it abuts the intermediate portion 8 is completely covered, 75 this being deemed desirable, since it is the sharp corners or edges which will readily crack off or shrink away from the material itself. By the arrangement shown, all raw or broken edges are completely covered and 80 the building wall as a whole will have a more sightly appearance. It will be understood that I preferably form the entire structure integrally, as shown, although it is 85 obvious that this integral formation is not necessary to the carrying out of the spirit of my invention. Therefore, I do not limit myself to integrally forming all of the parts 90 as they are illustrated.

What I claim, is:

A door or window frame comprising a trim portion terminating at its outer edge in a downturned flange, a substantially Z-shaped portion having both legs projecting

toward the door opening and the intermediate portion projecting toward the wall, said Z-shaped portion being attached to said flange and located beneath the trim, one of 5 the legs of said Z-shaped portion serving as a gage governing the plaster thickness and the intermediate portion serving as a plaster abutment, and a plurality of anchors secured

to the other leg of said Z-shaped portion and embedded in the building wall.

In testimony whereof I affix my signature in presence of two witnesses.

OSCAR LEONARD BAXTER.
